United States Patent Office

Des. 178,912
Patented Oct. 9, 1956

178,912

GASOLINE STATION

Rowell A. Billups and Guy C. Billups, Greenwood, Miss., and William L. Billups, New Orleans, La., assignors to Billups Petroleum Co., Greenwood, Miss., a corporation of Mississippi

Application August 30, 1954, Serial No. 32,065

Term of patent 14 years

(Cl. D13—1)

Fig. 3

Fig. 4

Figure 1 is a perspective view of a gasoline station, showing our new design;

Figure 2 is a side elevational view thereof;
Figure 3 is a front elevational view thereof; and
Figure 4 is a rear elevational view of the same.

We claim:

The ornamental design for a gasoline station, as shown.
